UNITED STATES PATENT OFFICE

153,588

DESIGN FOR AN OVERHEAD TRIM FOR A
WINDOW OR THE LIKE

Lewis Drnevich, East McKeesport, Pa.

Application October 19, 1946, Serial No. 134,105

Term of patent 7 years

(Cl. D54—2)

To all whom it may concern:

Be it known that I, Lewis Drnevich, a citizen of the United States, residing at East McKeesport, Pennsylvania, have invented a new, original, and ornamental Design for an Overhead Trim for a Window or the like, of which the following is a specification, reference being had to the accompanying drawings, forming part thereof.

In the drawings:

Figure 1 is a perspective view of a part of the overhead trim showing my new design; and

Figure 2 is a cross sectional view of the overhead trim shown in Figure 1.

I claim:

The ornamental design for an overhead trim for a window or the like, substantially as shown.

LEWIS DRNEVICH.
